UNITED STATES PATENT OFFICE.

EDWIN E. ANGELL, OF SOMERVILLE, MASSACHUSETTS, ASSIGNOR TO ANGELL MANUFACTURING COMPANY, OF BOSTON, MASSACHUSETTS, A CORPORATION OF MASSACHUSETTS.

PRINTING AND EMBOSsing APPARATUS.

No. 849,038.

Specification of Letters Patent.

Patented April 2, 1907.

Application filed January 25, 1906. Serial No. 297,809.

To all whom it may concern:

Be it known that I, EDWIN E. ANGELL, of Somerville, in the county of Middlesex and State of Massachusetts, have invented 5 certain new and useful Improvements in Printing and Embossing Apparatus, of which the following is a specification.

This invention relates to the art of printing, having particular reference to indelibly 10 or ineffaceably indicating the monetary value of checks, bonds, certificates, and other commercial papers to prevent alteration thereof.

Its object is to provide a machine or apparatus 15 of simple construction which will emboss the figures or other characters on the sheet and at the same time deposit ink or other coloring-matter on both sides of the sheet; the embossing having the effect of somewhat stretching the paper over the area 20 on which the color is deposited, so that the color will be more or less visible through the paper, whereby any attempt at erasure will cause an increased amount of color to be 25 visible, and so such attempt will be frustrated and detected.

The object thus is to practice the method and produce the article described and claimed in my pending application Serial No. 30 274,047, filed August 14, 1905.

In carrying out my invention I provide coöperating dies or types arranged in two sets or series, those of one set being raised to impress or emboss the sheet, while the dies of 35 the other set are recessed in their central portions to receive the raised dies and to imprint the outlines of the characters on the surface of the sheet immediately surrounding the parts thereof which are displaced or distorted by the raised dies.

These and other features of construction of the apparatus are described and claimed in the following specification and are illustrated in the accompanying drawings, in which—

45 Figure 1 represents a plan view of the machine with the upper part of the casing removed. Fig. 2 represents a vertical longitudinal section of the same. Fig. 3 represents a cross-section on line 3 3 of Fig. 2 looking toward the front. Fig. 4 represents a 50 sectional plan taken on line 4 4 of Fig. 2. Fig. 5 represents a longitudinal central section showing the parts in a different position

from that illustrated in Fig. 2. Fig. 6 represents a front elevation with the upper part of 55 the casing in section. Figs. 7 and 8 represent detail plan views of parts of the mechanism. Fig. 9 represents a detail elevation of the feed mechanism for the sheet upon which the impressions are made. Fig. 10 60 represents a detail sectional view on line 10 10 of Fig. 2. Fig. 11 represents a plan view of a fragment of a sheet, showing, on an enlarged scale, the appearance of characters impressed thereon by this apparatus. Fig. 12 65 represents a section on line 12 12 of Fig. 11. Fig. 13 represents a vertical transverse section, on an enlarged scale, of a pair of opposing printing and embossing dies.

The same reference characters indicate the 70 same parts in all the figures.

The mechanism of the apparatus is enclosed in a box or casing 1, which is divided into two parts by a flat horizontal partition 2, which constitutes a support for the sheet 75 of paper or other material which is to be printed upon. The upper part of the casing consists of a detachable cover 3, held in place by lugs 4, through which the walls of the cover screws may be passed.

80 Secured to the wall 2 is a support 5, which is fastened by screws 6 and extends forwardly from the point of attachment over the work-supporting wall, being separated therefrom by a space 7, which permits a 85 sheet of paper laid upon the wall 2 to be inserted under the support 5. The support 5 supports a die holder or head 8, which is preferably cylindrical and carries on its outer or cylindrical portion a plurality of marking 90 dies or types 9, which when the holder is rotated are brought successively into position directly above the supporting-wall 2, so as to act upon the sheet placed under them. The holder 8 is connected to a shaft 10, rotatable 95 in bearings 11 11 in the support 5, and is rotated to shift the dies by rotation of the shaft, this being accomplished through bevel-gears 12 13 from a vertical shaft 14, one of said bevel-gears being on shaft 10 and the 100 other on shaft 14.

Beneath the dividing-wall 2 is a second support or bracket 15, which has bearings 16 16 for a shaft 17, on the end of which is mounted a second rotary holder or head 18, 105 similar to the holder 8, which carries mark-

ing dies or types 19. The shafts 10 and 17 carry, respectively, gears 20 21, which mesh together, so that when the first is turned the second is correspondingly turned at the same time, and thereby the dies carried by each holder are shifted in unison. The dies or types carried by the holders represent certain definite characters—such as figures, letters, or conventional signs—and those on one holder correspond to the characters on the other and are similarly though oppositely arranged. Thus when one holder is in position to bring a certain character in position to mark the paper the other holder has the same character in position to mark upon the other side of the sheet. The dies 9 are recessed within the outlines of the characters, while those of the holder 18 are raised and designed so as to enter the depressions in the corresponding dies 9 when the holders are brought together. The raised portions 191 of the lower dies 19 are flat and adapted to receive ink, which when the dies are brought against the paper is deposited on the latter in solid masses which have the shape of conventional characters. On the dies or types 9 the narrow projecting surfaces which surround the recesses made to receive the protuberant lower dies are in one plane and receive ink, so as to deposit the same on narrow lines that surround and inclose the raised characters which are offset by the protuberant dies when the latter enter and force the paper into the recesses of the outline-dies.

In order to permit relative approach and separation of the die-holders, the bracket 15 is pivoted to the upper support 5 on an axis 22, which passes through the central point of contact of the gears 20 21, so that although the bracket 15 may oscillate the gears are retained at all times in mesh with each other, and when shaft 14 is rotated both the gears 20 and 21 are turned and both sets of dies correspondingly shifted, although they are out of engagement.

The means for rotating, and thereby adjusting, the die-holders consists of a lever 23, pivotally mounted so as to turn about a stud 24, secured to the bottom of the casing, and the rear arm of which carries a segment of a gear 25, meshing with a pinion 26, secured to shaft 14. Upon the forward arm of lever 23 is pivoted between lugs 27 an operating arm or handle 28, provided at its forward end with a finger-piece 29. The rearward end of operating-arm 28 is located directly above the pivot 24 and enters a recess 30, formed between the body of bracket 15 and a tongue 31. When the operating-handle is moved laterally to right or left, it turns lever 23 and rotates the die-holders through the connections above described; but its rear end does not change position and remains in engagement with the bracket 15. When, however,

the handle 28 is moved down around its pivot 32, its rear end is raised, whereby the bracket 15 is oscillated and die-holder 18 is raised to bring its uppermost die or type through a slot 33 in the supporting wall or table 2 and into contact with a sheet laid thereon. Separation of the dies is effected both by the weight of the lower die-holder and also by a spring 34, inclosed within a tubular socket 35 on the lever 23 and bearing against handle 28. 75

The die-holder 18 has a lateral flange 36, provided with slots or notches 37, which are spaced correspondingly to the spacing of the dies 19. 38 is a stationary finger projecting from the under side of wall 2 in position to enter the notch 37, which may be under it when the lower die-holder is raised. In case one of the notches is not directly beneath the locking projection the latter is engaged by the flange and the holder is thereby arrested 85 before it has been raised far enough to touch the sheet, and it cannot be raised farther until it has been shifted so as to bring one of the notches adjacent the lock. Thereby it is impossible to print upon the sheet except when 90 the dies are in the position necessary to make a correct impression, and this lock having once entered a notch prevents the dies being shifted while they are in contact with the paper. Thus it is impossible to spoil an 95 impression once made.

As a means for guiding the operating-handle laterally into a position which will adjust the dies correctly I provide notches 39 in the front wall 40 of the casing. The lower portions of these notches are just wide enough to permit the arm 28 to enter them, while the upper portions are widened and flared outwardly, so that one merges into the other. Thus no matter what position the operating-arm may be in when raised as soon as it is depressed it enters one of the notches and is guided thereby to bring the dies into correct adjustment for printing. The notches 39 are spaced so that when arm 28 is in one of them the locking projection 38 is in one of the notches 37 and the dies or types are exactly parallel with the paper.

On the forward top wall 41 of the casing is a line of index characters 42, corresponding to the characters on the dies or types and arranged so that when the operating-arm is under any one of the index characters the dies 9 and 19 bearing the corresponding characters are adjacent each other and in the line of centers of the die-holders. In the machine illustrated, which is adapted to print money values upon checks and other forms of commercial paper to prevent raising of the face values, the characters represent the numerals 115 from "1" to "0," inclusive, and also the signs representing dollars, pounds sterling, and francs. 120

Ink or other coloring-matter is supplied to the upper set of dies by means of rollers 43, 130

journalized in hangers 44, suspended from pivots 45 in lateral arms 46, extending from the upper part of support 5. These hangers are drawn toward each other and the holder 8 by springs 47, whereby the ink-rolls are retained in contact with the dies, and as the holders are rotated successive dies are brought against the rolls. An arm 44^a extends from each of the hangers, and these arms are held 10 against eccentric pins 46^a on screws 46^b, tapped into the arms 46 by said springs 47. Adjustment of these screws limits the pressure with which the rolls are held against the dies, so that the ink will not be squeezed out 15 too copiously, and also permits sufficient pressure to be maintained when the rolls have been reduced in diameter by wear. Similar ink-rolls 48 are mounted in holders 49, pivoted to arms 50, extending laterally from the 20 bracket 15 and held in engagement with the dies 19 by springs 51.

For feeding the sheet between impressions of the dies I provide one or more serrated or knurled feed-wheels 52 on a shaft 53, which 25 also carries a ratchet-wheel 54. An arm 55 is loosely journaled on shaft 53 and carries a stud 56, on which is pivoted a pawl 57 in position to engage the teeth of the ratchet. A spring 58 surrounds the stud 56, bearing at 30 one end against the arm 55 and at the other upon a projection of the pawl, and retains the toe of the latter against the ratchet. Arm 55 has a slot 59, into which extends the end of a rod 60, carried by the pivoted die-holder 35 bracket 15. When the latter is raised to impress the paper, arm 55 and pawl are carried over one of the teeth of the ratchet, and when the die-holder is lowered away from the paper its weight causes the arm to turn in the opposite direction, and therefore to turn the ratchet through the space of one or more teeth and advance the feed-wheel a step. This carries forward the paper so as to present a blank space for a new impression, and 40 overthrow is prevented by a frictional brake-spring 52^a, mounted on the casing and bearing against the hub 52^b of the feed-wheel. The paper is held in contact with the feed-wheels by a roll 61, journaled in a forked 45 holder 62 on a rock-shaft 63, to which is secured an operating finger-lever 64. When the latter is depressed, the pressure-roll is raised and separated from the feed-wheels, so that a sheet may be inserted or removed. A 50 spring 65 exerts a constant upward pull on the finger-arm 64 and holds the pressure-roll firmly against the feed-wheels.

As previously stated, the dies of the lower holder are raised, and therefore adapted to 55 impress the characters into the sheet and deposit solid blocks of coloring-matter while the coöperating dies are recessed. Thus when the dies are brought together the recessed ones bear at their outer edges upon the upper side of the sheet, while the raised

type force the portions of the paper inclosed within the outlines of the characters into the recesses. Thereby the characters are embossed or raised in the sheet, and lines of color surrounding the raised portions are 70 deposited on the upper side of the sheet, while solid masses of color are left upon the under side of the sheet in the concavities of the embossed characters.

Figs. 11 and 12 represent characters embossed upon a sheet 66, in which 67 represent the raised portions of the characters, 68 the lines of color outlining the characters entirely around the raised portions, and 69 represents the solid color deposited in the 80 concavities of the characters. In embossing the paper the portions which are displaced are somewhat stretched and attenuated, though without being perforated, and therefore the color deposited by the raised types 85 will show through to some extent. Preferably different colors are deposited by the recessed and raised types, respectively, so that in the upper side of the sheet contrasting colors will appear. Attempt to erase the 90 color on one side of the sheet will make the paper thinner, so that that deposited on the other side will show more plainly, and thus it is impossible to make any alteration without detection being certain.

It is to be understood, of course, that the relative arrangement of the types is immaterial, since, if desired, the embossing characters may be on the upper holder and the recessed or intaglio characters on the lower 100 holder.

I claim—

1. An apparatus of the character described comprising means for printing the outlines of characters leaving the interior portions 105 thereof blank, and means for displacing and stretching the portions of the material printed on within the said outlines.

2. An apparatus of the character described, comprising means for offsetting integral portions of a sheet, in the form of conventional characters, slightly away from the surface of the sheet, and means for impressing the sheet and depositing color on the surface thereof in lines surrounding and inclosing the offset portions of the same, thereby sharply defining the edges of the characters.

3. An apparatus of the character described comprising means for printing characters on one side of a sheet, and means for printing 120 on the other side of the sheet outlines of the same characters placed over and surrounding the characters first printed.

4. A printing apparatus comprising co-operating projecting and centrally-recessed 125 types adapted to print on opposite sides of a sheet and to displace the sheet between the portions thereof which are printed on.

5. A printing apparatus comprising co-operating types, one of which is recessed in 130

- its interior, and has projecting edges or lips adapted to impress the outlines of a character, while the other is protuberant and shaped to fit within the recess of the first.
5. A printing apparatus comprising co-operating types, one of which is recessed in its interior, leaving only the outlines of the character projecting, while the other is protuberant and shaped to fit within the recess 10 of the first, and separate means for inking the types.
7. A printing apparatus comprising co-operating types, one of which is recessed in its interior, leaving only the outlines of the character projecting, while the other is protuberant and shaped to fit within the recess 15 of the first, and means for coating each opposing type with a color different from that of the other.
20. A printing apparatus comprising a type-carrier having characters of which the edges are raised and the central portions recessed, a second type-carrier having raised characters corresponding to those of the first carrier and adapted to enter the recesses thereof, means for moving the carriers in unison to bring corresponding raised and recessed types adjacent, and means for bringing said types together to print.
30. A printing apparatus comprising holders carrying co-operating marking dies or types, said holders being simultaneously movable to shift the complementary dies and one relatively movable toward the other to print; and a single operating-arm mounted to swing in two planes and connected to said holders in such manner as to impart to them their die-shifting movement when swung in one plane, and to force them together for 35 printing when oscillated in the other plane.
40. A printing apparatus comprising a pair of holders carrying co-operating marking dies or types, both movable to alter the operative dies and one relatively movable toward 45 and from the other to print, a swinging arm in connection with both holders for adjusting them in unison, and an operating member connected to said arm for moving it, and engaged with the relatively movable holder for 50 moving the same toward the other holder.
55. A printing apparatus comprising relatively stationary and movable supports, holders rotarily mounted in said supports carrying co-operating marking dies or types, gearing connecting said holders for causing them to rotate in unison to shift their several dies correspondingly, and an operating member connected both to rotate said holders and to move the holder carried by the relatively 60 movable support toward the other holder.
65. A printing apparatus comprising relatively stationary and movable supports, holders rotarily mounted in said supports carrying co-operating marking dies or types, gearing connecting said holders for causing them to rotate in unison to shift their several dies correspondingly, and an operating member geared to the holders to rotate them and engaged with the relatively movable support to bring the dies together.
70. A printing apparatus comprising relatively stationary and movable supports, holders rotarily mounted in said supports carrying co-operating marking dies or types, gearing connecting said holders for causing them to rotate in unison to shift their several dies correspondingly, an arm in geared connection with said holders and movable to rotate them, and an operating-arm carried by said first arm and engaged with the relatively movable support for moving the same to bring the dies together.
75. A printing apparatus comprising relatively stationary and movable supports, holders rotarily mounted in said supports carrying co-operating marking dies or types, gearing connecting said holders for causing them to rotate in unison to shift their several dies correspondingly, an arm in geared connection with said holders and movable to rotate them, and an operating-arm carried by said first arm and engaged with the relatively movable support for moving the same to bring the dies together.
80. A printing apparatus comprising relatively stationary and movable supports, holders rotarily mounted in said supports carrying co-operating marking dies or types, gearing connecting said holders for causing them to rotate in unison to shift their several dies correspondingly, an arm in geared connection with said holders and movable in one plane to rotate them, and an operating-arm carried by said first arm movable in a different plane and engaged with the relatively movable support for moving the same to bring the dies together.
85. A printing apparatus comprising relatively stationary and movable supports, holders rotarily mounted in said supports carrying co-operating marking dies or types, gearing connecting said holders for causing them to rotate in unison to shift their several dies correspondingly, an arm in geared connection with said holders and movable in one plane to rotate them, and an operating-arm carried by said first arm movable in a different plane and engaged with the relatively movable support for moving the same to bring the dies together.
90. A printing apparatus comprising relatively stationary and movable supports, holders rotarily mounted in said supports carrying co-operating marking dies or types, gearing connecting said holders for causing them to rotate in unison to shift their several dies correspondingly, an arm in geared connection with said holders and movable in one plane to rotate them, and an operating-arm carried by said first arm movable in a different plane and engaged with the relatively movable support for moving the same to bring the dies together.
95. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm being engaged with the relatively movable die-holder to move the same toward the other holder to print.
100. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm being engaged with the relatively movable die-holder to move the same toward the other holder to print.
105. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm having a portion in line with the pivotal axis of the first arm engaged with the relatively movable die-holder for moving the same toward the other holder.
110. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm having a portion in line with the pivotal axis of the first arm engaged with the relatively movable die-holder for moving the same toward the other holder.
115. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm having a portion in line with the pivotal axis of the first arm engaged with the relatively movable die-holder for moving the same toward the other holder.
120. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm having a portion in line with the pivotal axis of the first arm engaged with the relatively movable die-holder for moving the same toward the other holder.
125. A printing apparatus comprising rotary die-holders carrying co-operating printing-dies, one holder being mounted for movement toward and from the other, an arm pivoted to move in one plane and in geared connection with said holders for rotating them to shift the dies, and an operating-arm pivoted to the first arm so as to move relatively thereto in a plane transverse to the first plane, said operating-arm having a portion in line with the pivotal axis of the first arm engaged with the relatively movable die-holder for moving the same toward the other holder.

5 ively thereto in a plane transverse to the first plane, said operating-arm being engaged with the relatively movable die-holder to move the same toward the other holder to print, and a spring between the two arms tending to hold the operating-arm so as to separate the die-holders. 35

10 18. A printing apparatus comprising rotary die-holders carrying coöperating printing-dies, one holder being mounted for movement toward and from the other, an arm pivoted to move in one plane and in geared connection with said holders for rotating them to shift the dies, an operating-arm pivoted to the first arm so as to move relatively thereto in a plane transverse to the first plane, said operating-arm being engaged with the relatively movable die-holder to move the same toward the other holder to print, and recesses arranged to receive the operating-arm when the latter is actuated for printing, to position the die-holders and dies. 40

15 19. A printing apparatus comprising rotary die-holders carrying coöperating printing-dies representing different characters, one holder being mounted for movement toward and from the other, an arm pivoted to move in one plane and in geared connection with said holders for rotating them to shift the dies, an operating-arm pivoted to the 45

first arm so as to move relatively thereto in a plane transverse to the first plane and movable with the first arm to set the same and thereby the dies by which an impression is to be made, said operating-arm being engaged with the relatively movable die-holder to move the same toward the other holder to print, and a scale adjacent the operating-arm bearing characters corresponding to those on the dies. 50

20 20. A printing apparatus comprising rotary die-holders connected for adjustment in unison, a series of coöperating marking-dies on each holder, one of the holders being relatively movable toward and from the other for bringing dies together to impress opposite sides of a sheet, an operating-arm engaged with said last-named holder, movable in one direction to bring the holders together and in a transverse direction to adjust the holders, and a plate adjacent the arm having tapered notches into which the arm moves when bringing the holders together, and by which it is guided to adjust the dies into exact registration. 55

In testimony whereof I have affixed my signature in presence of two witnesses.

EDWIN E. ANGELL.
